UNITED STATES PATENT OFFICE.

FRANK KACHUR, OF LORAIN, OHIO.

EXPLOSIVE BOMB.

1,277,940.

Specification of Letters Patent. Patented Sept. 3, 1918.

Application filed May 28, 1918. Serial No. 236,964.

To all whom it may concern:

Be it known that I, FRANK KACHUR, a subject of the King of Hungary, residing at Lorain, in the county of Lorain and State of Ohio, have invented certain new and useful Improvements in Explosive Bombs, of which the following is a specification.

The primary object of the invention is the provision of a bomb adapted to be transported without being accidentally discharged and ready for immediate use by dropping from an aeroplane.

A further object of the invention is to provide a bomb having an explosive charge adapted for firing upon an auxiliary or detonating charge, the complete firing operation being automatically accomplished when the device strikes an object during its course of travel.

20 A still further object of the invention is the provision of an explosive bomb that is easy and inexpensive to manufacture with the explosive material positioned for successive explosions which is accomplished when the bottom or sides of the device strike an object.

In the drawings forming a part of this application and in which like reference characters refer to corresponding parts throughout the several views,

Figure 1 is a side elevation of the device closed for transportation,

Fig. 2 is a top plan view thereof with the cover removed,

35 Fig. 3 is a side elevation of the same, showing the carrier in section,

Fig. 4 is a view similar to Fig. 3 of the carrier,

Fig. 5 is a central vertical sectional view 40 of the bomb proper,

Fig. 6 is a transverse horizontal sectional view of the same taken upon line VI—VI of Fig. 5 and

45 Fig. 7 is an enlarged detail horizontal sectional view of one of the firing members employed.

50 My device consists of a cylindrical bucket-shaped casing 10 having a screw-threaded cover 11 for closing the top thereof while a handle 12 is provided upon said cover for convenience in carrying the bomb.

A housing 13 similar in shape to the casing 10 is concentrically mounted within said casing and secured by means of a depending flange 14 carried by said housing

having screw-threaded engagement with a ring 15 carried by the bottom 16 of the casing 10, thereby spacing the housing centrally within the casing 10 for closing by means of the cover 11 having a depending 60 or thickened portion 17 engaging the top of the housing when the cover is closed.

A container 18 also in the form of a cylinder is centrally positioned within the housing 13 having legs 19 mounted in 65 sockets 20 upon the bottom 21 of the housing 13. The container 18 is adapted to be normally filled with dynamite 22 and closed by means of the thickened portion 17 of the casing cover. The space between the housing 13 and casing 18 is preferably filled with powder 23 while fulminating caps 24 are positioned in perforations 25 in the housing 13, it being evident that upon exploding one of the caps 24, the powder 23 75 will be ignited so as to explode and thereby explode the dynamite 22.

A firing pin 26 is slidably positioned through the casing 10 in axial alinement with each of the caps 24 and perforations 80 25, a firing point 27 being positioned upon the inner end of each of said pins. The outer end of each pin 26 is provided with a suitable head 28 and a spring 29 encircles the pin between the head 28 and the casing 85 10 for normally retaining said pins projected in their inoperative positions.

The manner of assembling as well as operating the device will be apparent from this detailed description of the same, it being seen that when the cover 11 is removed, the housing 13 may be readily secured within the casing 10 while the container 18 is then positioned within the housing and the intervening space filled with the powder 23. 95 The casing 18 is filled with the dynamite 22 either before or after the casing is inserted in the housing while the cover 11 when threaded upon the casing forms a closure for both the housing and the container and 100 also holds the container in said housing.

A suitable case or box 30 is provided for positioning the casing 10 therein for convenience in carrying without the liability of accidentally firing the bomb.

105 L-shaped supports 31 are positioned in the box 30 adapted for seating the casing 10 upon the base portions or feet 32 of said supports. Spaced lugs 33 are provided at four opposite sides of the casing 10 for 110

slidably positioning upon the supports 31 while a plurality of springs 34 carried by said supports bear against the casing 10 for maintaining the bomb substantially centrally of the box 30. When the bomb is positioned within the said box, the firing means including the heads 28 are positioned out of contact with the said box so that the pins 26 cannot be accidentally operated during the transportation of the bomb.

A hinged lid 35 is provided for the box 30 having a latch 36 for retaining the same closed while springs 37 are carried by lugs 38 within the box 30 for automatically 15 swinging the lid 35 upon its hinges 39 to open position when the latch 36 is released.

Handles 40 are provided upon opposite sides of the box 30 so that the box with the bomb positioned therein may be readily 20 carried and positioned in an aircraft such as an aeroplane. When it is desired to drop the bomb, the latch 36 is released for automatically opening the lid 35 and the bomb being grasped by its handle 21 is lifted 25 from the box 30 and dropped from the aeroplane upon any desired position of the enemy.

When any of the heads 28 strike an object, the pin 26 thereof pierces the adjacent 30 cap 24, igniting the powder 23 whereby the dynamite 22 is exploded. The simplicity of construction renders it possible to transport the separate parts of the bomb for assembling upon or near the field of action, 35 the assembling being also quickly and easily accomplished as the heads 28 of the firing pins 26 are threaded thereon and the caps 24 are easily positioned through the perforations 25.

40 What I claim as new is:—

1. In combination with a casing, an inwardly projecting annular ring upon the bottom thereof, a housing having a depending flange screw-threaded upon said ring, 45 a container mounted within said housing spaced therefrom and a cover for said container and housing in threaded engagement upon said casing.

2. In combination with a casing, an inwardly projecting annular ring upon the bottom thereof, a housing having a depending flange screw-threaded upon said ring; a container mounted within said housing spaced therefrom, a cover for said container and housing in threaded engagement upon said casing, dynamite filling said container, explosive powder filling the space between said container and housing and automatic ignition means for said power operable at a plurality of points, around the device.

3. In combination with a casing, an in-

wardly projecting annular ring upon the bottom thereof, a housing having a depending flange screw-threaded upon said ring, 65 a container mounted within said housing spaced therefrom, a cover for said container and housing in threaded engagement upon said casing, dynamite filling said container, explosive powder filling the space 70 between said container and housing, the said housing having perforations therethrough, fulminating caps within said perforations, a firing pin longitudinally slidably positioned through the said casing in 75 axial alinement with the adjacent cap and perforation and means adapted for normally holding each of said pins in its inoperative projected position.

4. A bomb comprising a bucket-shaped 80 casing, a threaded ring within said casing upon the bottom thereof, a housing having an annular depending flange screw-threaded upon said ring, sockets upon the bottom of said housing, a container within said housing having legs seated within said sockets, a cover screw-threaded upon said casing having a thickened portion adapted for overlying said housing and container when the cover is closed and a handle upon said 90 cover.

5. A mob comprising a bucket-shaped casing, a threaded ring within said casing upon the bottom thereof, a housing having an annular depending flange screw-threaded 95 upon said ring, sockets upon the bottom of said housing, a container within said housing having legs seated within said sockets, a cover screw-threaded upon said casing having a thickened portion adapted for 100 overlying said housing and container when the cover is closed, a handle upon said cover, dynamite within said container, explosive powder between said container and housing, fulminating caps positioned through 105 the sides and bottom of said housing adapted for igniting said powder when exploded, and firing pins for said caps provided through said casing and normally positioned projected out of contact with 110 said caps.

6. In combination with a bomb casing, outwardly projecting pairs of lugs carried thereby, a receiving box for the bomb having a hinged lid, supports within the box 115 having inwardly projecting feet adapted for supporting the casing when positioned within the box, with the supports positioned between said lugs and positioning springs carried by said supports in contact with 120 said casing when positioned therein and automatic opening means for said lid.

In testimony whereof I affix my signature.

FRANK KACHUR.
